(57) CLAIM

The ornamental design for a bath towel basket, as shown and described.

DESCRIPTION

FIG. 1 is a front, right and top perspective view of a bath towel basket, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the bath towel basket that form no part of the claimed design.

1 Claim, 8 Drawing Sheets
